VENTILATOR

Filed Oct. 10, 1929

UNITED STATES PATENT OFFICE

ABRAHAM S. WEINSTEIN, OF BRIGHTON, MASSACHUSETTS

VENTILATOR

Application filed October 10, 1929. Serial No. 398,658.

This invention relates to devices for the tops of ventilating pipes, and has a particular relation to that type of such devices as are known as cowl ventilators.

5 Among the objects of the invention are the following:

(a) To provide a cowl ventilator having a maximum ventilating efficiency, that is, one which will produce the most effective 10 draft upwardly through the ventilator pipe with which it coacts.

(b) To provide a cowl ventilator so constructed that the volume of working air blown therethrough is several times greater 15 than the amount of air which passes through a ventilator of the type now in general use and of the same size.

(c) To provide a ventilator having means 20 to prevent foreign undesirable matter, such as water mist, from entering thereinto.

(d) To provide a ventilator so constructed 25 that the wind inlet thereto is of smaller area than the wind entrance so that a maximum suction effect is attained at the wind inlet.

(e) To so construct the ventilator that the back thereof is always kept toward the wind, and the foul air outlet always facing 30 away from the wind.

(f) To provide a means for preventing a 35 back draft in that portion of the cowl where the suction is weakest.

(g) To so construct the edges of the several annular members composing the cowl 40 as to create an "air spray" at the wind inlet thereto.

(h) A general disadvantage of cowl ventilators now in general use is that they will 45 function to produce a draft only when the wind is blowing horizontally or upwardly, but not when they are subjected to downward gusts of wind. It is therefore an object of this invention to overcome this deficiency and provide a cowl ventilator which will 50 operate irrespective of the direction in which the wind is blowing.

Other objects of the invention will become apparent from the detailed description 55 thereof given below.

These objects are attained by the mecha-

nism illustrated in the accompanying sheet of drawing, where

Figure 1 is a diagrammatic view, partly 55 in elevation and partly in section through the ventilator;

Figure 2 is a diagrammatic showing of the shape and relative size of the average wind entrance;

Figure 3 is a diagrammatic showing of 60 the shapes and relative sizes of the wind inlets;

Figure 4 is a fragmentary enlargement of 65 a portion of Figure 1, illustrating the formation of the "air spray" into the ventilator; and

Figure 5 is a fragmentary section similar 70 to Figure 1, illustrating a modified form of the invention;

Figure 6 is a fragmentary side view of 75 Figure 1, as seen from right to left, and particularly illustrating the back draft preventing baffle.

Similar reference numerals refer to similar parts throughout the several views.

In the modification of the invention illustrated in Figure 1, reference numeral 1 indicates the vent pipe which usually protrudes above the roof of the building or like to be ventilated, and with which the 80 ventilator coacts. The vent pipe 1 is generally similar to the ordinary vent pipes now in use, with the important exception that for any specified capacity of applicant's improved ventilator, the vent pipe is 85 of much smaller diameter than the pipe used with the usual ventilator of corresponding capacity. This is due to the increased capacity of applicant's ventilator of any specified size as compared with the capacity of 90 the ordinary ventilator now in general use of corresponding size. Thus for any specified capacity, applicant may employ a smaller size of ventilator and correspondingly smaller vent pipe and still obtain the 95 same or greater amount of ventilation. How this increased capacity is attained will be apparent from the detailed description of the construction of the improved ventilator given below.

Mounted upon the vent pipe 1, and in 100

telescoping engagement therewith, is the ventilator barrel 2, which constitutes the supporting means for the ventilator.

The ventilator may be rotatably supported upon the barrel 2 in any well known manner. The preferred supporting means (as shown in Figure 1) comprises a plurality of bracing means 3 which are adapted to house a spindle rest 4. This spindle rest is formed in the shape of a vertically-extending, somewhat elongated cup. At the bottom of the cup is disposed a glass ball 5 which acts as an antifriction vertical thrust bearing.

15 The spindle rest 4 is also adapted to contain a quantity of lubricant, if desired, whereby to keep the end of the spindle 6 thoroughly lubricated. The lower end of the spindle 6 is received in the cup-shaped 20 spindle rest and the spindle extends vertically therefrom. Between the upper end of the bracing means 3 and the spindle 6, antifriction bearing means 7 may be disposed.

25 The ventilator proper is made up of a plurality of frusto-conical ring-shaped or annular sheet metal members of a maximum width on one side and gradually decreasing in width to a point of minimum width diametrically opposite the point of maximum width. These annular members are indicated in Figure 1 of the drawing by reference numerals 8, 9, 10, 11, 12, 13 and 14. An important feature of these ring-shaped 35 members is that they progressively increase in diameter, the lowermost member 8 being of smallest diameter while the uppermost member 14 is of greatest diameter.

40 The ventilator as a whole is substantially elbow-like in shape as a result of the disposition of the annular members thereof in overlapped relation with their respective portions of minimum width in contact and united together as by welding or in any 45 other desired manner. This leaves the remainder of the annular members also in overlapped relation with respect to each other, but in addition they are spaced from each other by a crescent-shaped space, as is 50 shown diagrammatically in Figure 2. The crescent-shaped spaces form wind passages 15 which are of substantial extent due to the substantial extent of the overlap of the members. These spaces or wind passages 15 are 55 widest at the outermost or lowermost ends or portions where they constitute wind entrances 16. The passages then converge inwardly to a minimum width at the innermost or uppermost ends of the passages 15 60 to form wind inlets 17 to the interior or throat of the ventilator.

65 Extending downwardly from the member 8 and into telescopic relation to barrel 2 is the ventilator rim 18. This rim member also extends upwardly into overlapped relation

with the member 8 in the same way as above described in connection with the several annular members, and as clearly illustrated.

The uppermost member 14 is shaped as shown to constitute the ventilator outlet. 70

The several annular members and ventilator rim are connected to each other and to the spindle 6 by a plurality of strap-like members 19 and 20.

75 As a consequence of the difference in diameters of the several annular members, as above described, the ventilator may be shipped in disassembled form by placing the annular members one within the other. This is particularly advantageous in the case of large ventilators, which as a result of the novel construction described, may be shipped in a comparatively small crate, thus diminishing the cost of crating, shipping, transporting, and handling thereof on the job. 80

85 The top of the ventilator is provided with the usual vane 21, whereby the ventilator outlet is always kept facing away from the wind.

90 Coming now to the peculiar and novel structural characteristics of the annular members, it is seen that the lower or outer edge of each member is flared outwardly. These flares 22 act as deflectors for the wind which is caught by the flared portions and deflected into the interior of the ventilator. In the case of the upper members 12 and 13, the inner sides of the flares 22 act as guides for horizontal wind currents, while the outer sides of the flares act as guides for downwardly directed wind currents. Upwardly directed currents are deflected inwardly by the flares 22 on members 8, 9, 10 and 11. It is thus seen that the improved ventilator functions irrespective of the direction of the wind currents. 105

110 The upper or inner edge of each of the annular members is also flared, as at 23. These flares or raised edges 23 extend into close proximity to the adjacent annular member and prevent the entry into the ventilator of any undesirable foreign matter, such as water mist. The rim 18 is also formed with a flare 23.

115 Directly adjacent each raised edge 23, the next adjacent member has formed thereon a bead or raised portion 24 in order to form a clear opening at the inner ends of the several passages 15. These clear openings constitute the wind inlets 17. At the same time, the beads 24 act as stiffeners for the annular members. 120

125 The raised edges 23 and beads 24 are so shaped as to form an "air spray" of the wind currents passing through the inlets 17. As is shown in Figure 4, the passages 15 converge from the wind entrances to the wind inlet openings. Wind currents entering these passages are compressed as a result of this convergence and store up energy, which is suddenly released as the currents 130

pass by the wind inlet 17 and suddenly expand to form an "air spray" with a markedly efficient sucking effect. The course of the air or wind currents is clearly illustrated by 5 the arrows in Figure 3 of the drawing.

The upper part of the outlet annular member 14 is shaped to permit a free upward and outward flow of the foul air.

The lowermost portion of the outlet opening 10 is provided with a shield or baffle member 26 so shaped and placed as to prevent any possible back draft through the outlet opening which might attempt to take advantage of the relatively small outward 15 wind pressure at this point.

Counterbalance weight 27 is provided in the rear of the ventilator so as to prevent binding of the latter in its rotation.

As a result of the construction above described, it is apparent that the diameter of the ventilator increases progressively from a minimum at the rim member 18 to a maximum at the outlet member 14. This enables 20 the throat of the ventilator to efficiently accommodate the wind which passes therethrough in constantly increasing amount from the bottom to the top of the ventilator.

Referring now to Figure 3, it will be seen that the total area of the several wind inlets 30 is at least double the area of the vent pipe 1. The wind entrance openings are at least twice as wide as the wind inlets, and consequently have a total area of at least four times that of the vent pipe. Thus a comparatively large volume of air enters the ventilator at the wind entrances. This volume is several times that which passes through the ventilator now in general use of corresponding size, and is the telling 35 factor in the greater efficiency of applicant's ventilator.

The modification shown in Figure 5 is of the same construction as the modification above described, with the following exception. The uppermost annular members 12 and 13 are provided at the tops thereof with parti-circumferentially extending slots 28 formed by punching out the material of the 40 members. Disposed along one side of these slots and secured to the members by soldering or welding, are substantially vertically disposed baffle or deflector elements 29. These deflector elements augment flared portions 45 of these members by guiding downwardly directed wind currents into the interior of the ventilator.

Various changes in the form, proportions and minor details will be obvious to those 50 skilled in the art without departing from the spirit and scope of the invention. Hence I consider myself entitled to all such changes as fall within the scope of the following claims.

Having thus described and illustrated the

invention, what is claimed as new and desired to secure by Letters Patent is:

1. In a ventilator of the class described, a plurality of annular members arranged in substantially vertical and overlapped relation, said members comprising a lowermost rim member, an uppermost outlet member, and a plurality of intermediate members, and means on said intermediate members to deflect downwardly-directed air currents into 70 said ventilator, whereby the ventilator is adapted to effect its intended function when exposed to downwardly-directed currents.

2. In a ventilator of the class described a plurality of annular members arranged in substantially vertical and overlapped relation, said members comprising a lowermost rim member, an uppermost outlet member, and a plurality of intermediate members, the uppermost of said intermediate members 75 being provided with means to deflect downwardly directed wind currents into the interior of the ventilator.

3. A cowl annulus having a passageway therethrough, means disposed adjacent said passageway and extending outwardly of said annulus and adapted to deflect air currents into said passageway, said annulus having a substantially centrally disposed bead thereon, and the inner edge of said annulus being 90 outwardly flared.

4. In a ventilator of the class described, a plurality of substantially vertically disposed overlapping annular members of different diameters, said members being connected together to contact only at one side thereof, whereby to form a plurality of crescent-shaped openings therebetween, and the uppermost of said annular members defining the ventilator outlet, coacting means on adjacent members for introducing suddenly expanding air sprays into the interior of the ventilator irrespective of the direction of blow of the wind, the intensity of said sprays varying at different points according 100 to the width of said openings at said points, and a baffle member disposed adjacent the narrowest part only of said openings where the force of said air sprays is weakest, and extending into and partially obstructing the lower portion of the ventilator outlet, whereby back draft into the ventilator is prevented.
